UNITED STATES PATENT OFFICE.

JOHN BARRETT, OF MONTREAL, QUEBEC, CANADA.

SAFETY-POCKET FOR TROUSERS.

1,075,240.

Specification of Letters Patent.

Patented Oct. 7, 1913.

Application filed November 20, 1912. Serial No. 732,553.

To all whom it may concern:

Be it known that I, JOHN BARRETT, a resident of the city of Montreal, in the Province of Quebec and Dominion of Canada, have invented certain new and useful Improvements in Safety-Pockets for Trouser; and I do hereby declare that the following is a full, clear, and exact description thereof.

10 Currency and other things are frequently lost from the trousers pockets when gentlemen are reclining owing to the walls of the pockets leading in an even line to the mouth of the pocket, and to obviate this without 15 encumbering the pockets with attachments or complications of any kind is the object of my invention.

The invention may be said, briefly, to consist of a one piece pocket, the rear wall of 20 which has a horizontal extension or sub-pocket at an acute angle to the main length of the pocket; the extension or sub-pocket being supported against sagging by a strap hung from the waistline of the trousers.

25 For full comprehension, however, of my invention reference must be had to the accompanying drawings forming a part of this specification in which similar reference characters indicate the same parts, and wherein:

30 Figure 1 is a rear view of a portion of a pair of trousers with my improved pocket attached and illustrated in elevation, and Fig. 2 is a horizontal sectional view taken on line A A, Fig. 1.

35 The portion of one side of a pair of trousers is indicated at b, the opening forming the mouth of the pocket being indicated at b' and the waistline at c. The pocket is made by folding a single piece of pocket- 40 material on itself on a straight line forming the front edge d, and it is cut to present substantially straight edges e forming when stitched in place the upper portion of the

rear edge of the pocket. A rearwardly extended sub-pocket k forms the lower portion 45 of this rear edge and is presented by cutting in a line f at a slight acute angle to the line e. From the end of this line f the cutting extends in a gentle curve as at g and forms the bottom of the pocket terminating 50 at the forward edge d. These off-set lines f, g of the respective inner and outer sides of the pocket are stitched together. This sub-pocket is preferably supported and kept 55 in position to have open communication with the main pocket by a strap m stitched at its upper end at the waistline and its lower end to the apex of the sub-pocket.

When the wearer assumes a reclining position the currency or other loose articles in 60 his pocket will follow the curved line g and be lodged in the sub-pocket k and thus be prevented from falling from the main pocket.

What I claim is as follows:—

1. The combination with a pair of trousers of a side pocket having an integral sub-pocket extending rearwardly from the lower portion of the rear edge of the main pocket and at an acute angle to the upper portion 70 of said rear edge and supplemental supporting means for said sub-pocket.

2. The combination with a pair of trousers, of a side pocket having a sub-pocket extending rearwardly from the lower 75 portion of the rear edge of the main pocket and at an acute angle to the upper portion of the said rear edge and a strap supporting the sub-pocket.

In testimony whereof I have signed my 80 name to this specification in the presence of two witnesses.

JOHN BARRETT.
